Fig. 4.

Fig. 5.

This technical drawing depicts a vertical assembly, likely a component of a larger machine or structure. The drawing is annotated with numerous numbers, possibly indicating part numbers or specific measurements. Key features include a central vertical column with a stepped profile, a horizontal plate or bracket labeled '16' attached to the left side, and a complex assembly of plates and bolts at the top labeled '51' and '53'. Other labeled parts include '29', '31', '37', '44', '30', '14', '35', '17', '72', '29', '35', '49', '26', '15', and '74'. The style is characteristic of early 20th-century engineering drawings.

RAILWAY CAR

Karl F. Nystrom, Milwaukee, Wis.

Application April 10, 1934, Serial No. 719,867

9 Claims. (Cl. 105—401)

This invention relates to the construction of passenger vehicles, and, more particularly, to the construction of railway cars.

One of the objects of the invention is the provision of a new and improved railway car which is light in weight and the walls of which are provided with novel insulation and sound deadening instrumentalities.

Another object of the invention is the provision of new and improved means whereby the finish and fittings of the interior side walls of railway cars may be manufactured and applied at a minimum of time and expense.

Another object of the invention is the provision of new and improved means whereby the finish panels of the interior side walls of passenger cars may be standardized in form, shape, construction, and the method of attaching the same and the application of the fittings to be made uniform to the end that car construction may be simplified and the cost of manufacturing greatly reduced.

A further object of the invention is the provision of new and improved means whereby separate manufacturers may supply the finish and fittings in completed form, and the car manufacturers may apply the same without change and without the use of special tools or additional fastening means; in this way, the entire finish and fittings of a car may be readily changed at a minimum of time and labor, as occasion or necessity may require.

Other and further objects and advantages of the invention will appear from the following description taken in connection with the accompanying drawings, in which:

Fig. 1 is a longitudinal, vertical section of a railway car embodying the invention, with parts broken away, the ceiling insulation being shown out of proportion for the sake of clearness;

Fig. 2 is a transverse section on the line 2—2 of Fig. 1, with parts broken away;

Fig. 3 is a section on the line 3—3 of Fig. 1;

Fig. 4 is a section on the line 4—4 of Fig. 1, with parts broken away and parts removed for the sake of clearness;

Fig. 5 is a section on the line 5—5 of Figs. 1 and 4;

Fig. 6 is a section on the line 6—6 of Fig. 1;

Fig. 7 is a transverse section on the line 7—7 of Fig. 1 showing the outer wall or skin of sheet metal entirely surrounding the car, with parts removed for the sake of clearness.

Fig. 8 is a section on the line 8—8 of Fig. 5.

55 The conventional passenger cars are practi-

cally of metal throughout. As a result, the cars are heavy and costly to manufacture and operate. The present invention seeks to materially reduce the weight of these cars by the use of sheet metal exterior and composition interior 5 finish or trim.

It is the common practice in applying the interior finish and fittings of railway cars and the like to permanently attach the same in position thereon. This arrangement is expensive due to 10 the large amount of work required to permanently secure the same in position which is usually done by the aid of screws, rivets, bolts and the like, all of which consumes a large amount of time in assembly work, and when applied the 15 finish and fittings are extremely difficult to remove.

In order to overcome these difficulties, the finish, according to the present invention, is cut to size and detachable interlocking fastening means 20 are employed to hold the finish in position on the car frame and the wall fittings are likewise provided with detachable attaching means whereby they may be attached and detached at will.

The finish panels are preferably of composition material and are light in weight, so that the 25 total weight of the finished car is materially reduced.

Referring now to the drawings, the reference character 5 designates a railway car body having 30 the usual passenger compartment 2 in which are the double seats 3 adapted to swing about a pedestal 4. These seats are located opposite the space between the windows whereby warm air with which the car is heated in cool weather may 35 be discharged beneath the seats and the passenger may control the raising of the windows without inconveniencing passengers who may be seated behind him, since any draft will strike him rather than such other passengers.

Furthermore, the seats may be turned to position to have access to the side walls of the car for removing or replacing panels on said wall as will presently appear. The car is also provided with a rest room or lavatory 13, a portion 45 of which is shown in Fig. 1, and a toilet and vestibule, not shown.

The partition between the lavatory and the passenger compartment is shown at 30 and the passage or corridor leading from the passenger compartment to the vestibule is shown at 40. Since the arrangement of the vestibule and toilet in the car is conventional, it was not thought necessary to illustrate or describe the same.

The body is provided with side walls 6, the 55

roof 8 and floor 9. If desired, the floor of the car may be of composition material. The side walls are provided with windows 10 at intervals throughout their lengths, as is usual in such 5 constructions. These windows are arranged adjacent the plane of the outer surface of the car, thereby reducing wind resistance to a minimum.

The body frame of the car comprises the sills 10 11 extending longitudinally of the car, and the cross members or floor beams 12 (see Fig. 1) for supporting the floor 9.

Extending upwardly from the side sills at each side of the car are the side posts 17 and 18 (see 15 Figs. 1, 5, and 6). They are curved inwardly adjacent their lower ends at opposite sides of the windows and are attached to the side sills 11. At their upper ends they are attached to the top plate 19 extending longitudinally of the car. 20 The carlines 21 extend upwardly from the plates 19 and are arched over the car from one side plate to the other for supporting the roof 8, as is usual in such constructions. Attached to the carlines 21 and extending across from side to side of the 25 car are the furring supports or bars 22 (see Figs. 1 and 2) for supporting the ceiling 23 which is rigidly attached thereto. These bars are spaced from the roof and are supported by brackets 13 extending longitudinally of the car.

30 In the space above these bars is adapted to be secured the main air duct 24 of the air conditioning system with which the car may be equipped. This duct is supported by brackets 7 from the ceiling supports 22. Branch conduits or ducts 25 extending downward between the inner and outer walls at each side of the car between the side posts 17 and 18 between the windows supply conditioned air to the car.

During the winter season, warm air is delivered 40 through the discharge openings 26 beneath the seats 3 which are located opposite the space between the windows. In warm weather, cool air is delivered through the upper discharge openings 28 above the seats.

45 The sides of the car are provided with inner and outer walls spaced apart for enclosing the side posts. The outer wall 29 is of sheet metal and extends continuously over the sides and roof of the car. Preferably, though not necessarily, this sheet extends entirely around the car forming what may be termed a skin for enveloping the car, as shown more clearly in Fig. 7. The parts are welded together to form a continuous band. The skin or outer wall may be spot welded, or 50 otherwise rigidly connected to the side posts, top plates and carlines. This skin will resist torsional strains of the body.

In order to prevent undue vibration and to 60 deaden the sound, this outer wall may be and preferably is coated on its inner side with a composition material 31 suitable for this purpose. This car wall may also be painted on its inner side with aluminum paint or it may be lined with a bright metal foil or thin aluminum plate to 65 reflect the heat and prevent its being conducted through the car wall in either direction.

The inner wall or trim of the car is composed of a plurality of preformed panels which are detachably secured in position. These panels are 70 molded to shape and finished in completed form before they are applied. As, for instance, if the trim is to be embossed, painted or embellished in any manner, this is done before the panels are connected to their supports and when assembled 75 the car walls are complete. This is considered an

important feature of the invention because it permits the use of composition material in forming the panels of any desired shape, thereby reducing the weight of the car very materially.

This material may be molded to the desired 5 form or shape during its manufacture, or it may be given the desired shape after manufacturing. In any event, it is preformed before being applied and may be covered with cloth or other suitable material of a selected pattern and color scheme. 10 By this means, the interior finish of the car may be standardized so that the minimum number of parts are required.

In the construction shown, only three different 15 shapes or forms of panels are required for the intermediate portion of the sides of the car. This standardizing of the finish obviates the necessity for the services of experts in applying the finish trim to the car, and, furthermore, the panels may be applied with the minimum of time and labor. 20

In the space above each window, a header or window trim panel 32 of composition material is applied. This panel has its lower edge conforming to the shape of the window frame or trim 33. The side edges of the panel are adjacent to the 25 side posts 17 and 18 and the panel is held in spaced relation from the outer wall by spacers 35 (see Fig. 6) which are held in position against the outer wall by angles 36 welded to the posts 17 and 18. The upper edge of the panel is concealed by 30 a trim rail 42 extending longitudinally of the car between the pilasters at the sides of the windows, and its lower edge may abut the window frame or trim 33 or be concealed thereby, as 35 shown in Fig. 2.

The trim 33 may be removed by removing screws 40 which hold it in position. These panels 32 are secured in position by suitable clips 37 that detachably engage a flange of the angle 36. Any suitable form of detachable clips may be employed. Those shown are in use and comprise a head portion 38 (see Figs. 5, 6, and 8) concealed in the panel or secured to the outer side of the panel, and two resilient fingers 39 and 41 extending outwardly from the head portion which are 45 adapted to be inserted through an opening through the adjacent flange of the angle 36. The fingers diverge from the head and then converge toward their outer ends to provide a swelled or enlarged portion which, when the arms are in- 50 inserted through the opening, expand and engage the outer side of the flange for retaining the parts in position. A suitable number of these clips are employed for retaining each panel in position.

In applying the panel, it is only necessary to 55 cause the arms of the clip to enter the corresponding opening and then push the clips home. The panel is removed by the reverse process—by pulling outwardly on the panel.

In the space beneath the windows, a wainscot- 60 ing panel 44 is applied by spring clips in the same manner to the inner flange of the side posts as the window panel 32 (see Fig. 7).

Extending above the floor of the car along the 65 car sides is a mop board 45 of sheet metal or other light sheet material. This sheet extends from beneath the floor to a short distance above the floor and is straight longitudinally of the car and extends over the frame posts 17 and 18, as 70 shown more clearly in Fig. 5. This board may be, and preferably is, welded to the inner flanges of the posts 17 and 18, as at 46 and 47. The upper edge of the mopboard 45 is offset outwardly beneath the windows (see Fig. 3), forming a ledge 75

or shoulder 48 against which the lower edge of the panel 44 abuts.

A pilaster panel 49 is applied over the side posts 17 and 18 between the windows (see Fig. 6). The panel adjacent its side edges is preformed into enlarged portions 51 for decorative purposes. The side edges are bent to extend outwardly and engage the posts 17 and 18 and abut against the panels above and below the window for assisting in holding those panels in position.

The pilaster panels may be secured in position by clips 37, the heads of which are secured to the outer side of the panels, or are concealed within said panels. These clips engage in openings in the inner flanges of the side posts 17 and 18 (see Fig. 6) in the manner described above.

Each of the panels 49 is provided with an upper opening 28 through which cool air from the duct 25 is discharged, and a lower opening 26 opposite a corresponding opening in the duct is provided below the panel for the escape of warm air for heating the car (see Figs. 1 and 4).

A removable rack cove panel 52 is provided for forming a finish beneath the baggage rack 53 (see Fig. 2). This panel is preformed, as shown in said figure, and its lower edge is received in a metal trim 54 secured to the wall of the car and extending longitudinally thereof. Its upper edge engages in a recess 55 in the outer end of the package rack. The connections between the ceiling support and carlines is concealed by a ceiling cove panel 56 (see Fig. 2), the upper edge of which is secured to the ceiling 23 by suitable fastening means, including a finishing strip 57. The lower edge is received in a rabbet of a panel 58 which constitutes the back of the rack 53 when the same is in position on the wall.

The trim on the ends of the car are removably attached by clips 37 in the manner described above. The end panel 90 on the partition wall 91 may be embossed to represent one or more panels, as shown at 92, or any other desirable figure may be embossed on this or any or all of the panels.

The partition wall 91 between the passenger compartment 2 and the lavatory or rest room 13 (see Fig. 1) has a heat radiator 94 concealed within the same and the wall has an upper discharge opening 95 and a lower intake opening 96 whereby when the car is not in use it may be kept above freezing in cold weather by air in its natural circulation across this heater. The panel 90 is positioned between these openings as indicated in Fig. 7.

Any or all of the trim panels may be and preferably are covered with fabric, as shown at 99 (see Fig. 6) of the desired pattern and color scheme or the panels may be painted or otherwise treated to obtain the desired color and design.

It may be desirable to remove the entire trim on the walls of the car for the purpose of cleaning, redecorating or for changing the design. In order that this may be readily accomplished, the fittings for the interior of the car, such as the baggage racks 53 and the electric light fixtures 59 (see Fig. 2) and the window trim 33 are removable. As shown, the baggage rack comprises the basket portion 61 and the supporting brackets 62 which are provided with means such as the hooks or enlarged portions 63, 64, and 65 on the brackets for engaging in slots in the side posts 17 and 18 for detachably holding the brackets in position on the side walls of the car.

When it is desired to remove the baggage racks, the same are elevated to disengage the hooks from

the lower edges of the slots and then the rack is moved outwardly to detach the hooks from the slots.

The lamps are mounted in the baggage rack cove and the lamp fittings are shaped to conform to the panel 52. Each fitting is provided with a supporting arm 66 having spring jaws or fingers 67 which are adapted to engage a bar 68 supported by brackets 69 which in turn are secured to the side wall of the car. The supporting arm 66 extends through the panel 52 when the lamp is in position in the car.

When it is desired to remove the lamp fixtures, it is only necessary to force the same outward to disengage the spring fingers 67 from the supporting rod 68.

It will thus be seen that when it is desired to remove the trim from the inner sides of the car, the lamps and racks are first removed and the seats are rotated through 90°, as indicated by the dotted line position for one of the seats in Fig. 1 to give access to the walls, after which the panels are removed by forcing the same inwardly for detaching the clips from their cooperating openings.

The panels may be replaced or other panels of different designs, style or finish may be substituted, as occasion may require. For instance, panels of one color or design may be employed in the summer and a different color or design during the winter, since the changes may be effected with little time and expense.

As the inner and outer walls of the car body are thin and light, it is desirable that suitable insulation be provided between these walls to prevent transference of heat through the walls of the car.

Any suitable form of insulation may be employed. In the form of construction disclosed, a plurality of thin sheets or panels spaced apart and inserted between the inner and outer walls of the car and extending about the entire body between the frame members are employed for this purpose. These thin panels are adapted to prevent convection of air between the inner and outer walls of the car, thereby preventing the transference of heat through said walls.

Any suitable means may be provided for supporting these panels. Fig. 5 shows a section through the wall through one of the pilasters, and Fig. 4 shows a section through the mophboard. The insulating panels 71, of which there are three in the form shown, are held in position by spacer blocks 72 and 73 secured within the channel of the side posts 17 and 18. These blocks may be of any suitable material, as wood or composition. They are provided with kerfs in which are secured plates 74 having openings in their outside ends for receiving the clips 37 which are applied in the manner described above for securing the finished panels to the interior of the car.

Only two insulating panels 71 are employed in the pilaster above the lower opening 26 because of the presence of the branch conduit 25. The panels 71 are arranged outwardly of the conduit 25. The roof is also provided with a plurality of insulating panels 75 which are also arranged in spaced relation between the carlines, as in the construction just described.

The space between the floor 9 and the outer wall 29 is also provided with a plurality of thin light insulating panels 76 which are also held in operative position by spacer blocks, as described above. The space 77 immediately above the windows is not provided with insulating panels for 75.

the reason that this space is occupied by a spring roller 78 on which is wound the cable 79 attached to the sash of the window 10 for counter balancing the weight of same. The window shade roller 81 is also mounted in this space. In cars which are constructed without movable windows, this space may also be provided with insulating panels supported by frame or spacer blocks, as described above. These spacer blocks may be rigidly mounted in place with the panels detachable, as described above, or they may constitute frames in which the panels are permanently engaged, as indicated at 82 in Fig. 2 of the drawings. These insulating panels are preformed and may, if desired, comprise two parts, one of composition or non-conducting material 83 and the other a thin panel having a heat-reflecting surface, as the thin sheets 84 (see Fig. 8 of the drawings). These panels may be connected by clips 37 in the manner already described. It will thus be seen that the roof, side walls and floor are all insulated by a plurality of panels forming a plurality of dead air spaces which prevent transference of heat through either the roof, sides or floor of the car.

I claim as my invention:

1. In a railway car having a plurality of upstanding side posts having side flanges provided with openings therein, windows secured in the sides of said car, a frame extending about said windows, attaching plates on said frames, detachable panels and pilaster plates constituting the side walls of said car, clips for engaging said panels and the openings within said side flanges for removably holding said panels in position, baggage racks and lamp supports detachably connected to said side posts whereby said panels, racks and lamp supports may be readily attached and detached from the side wall of said car.
2. In a car having a frame and an outer side wall, an inner wall detachably connected to said frame, fittings for the interior of said car comprising a baggage rack detachably connected to said frame, a detachable preformed panel beneath said rack for forming a rack alcove and a lamp fitting detachably mounted within said alcove, said fittings and panels being readily removable from the sides of said car.
3. A railway car comprising inner and outer walls, said inner walls comprising preformed panels of thin sheet composition material, supports for said walls, a baggage rack, means for detachably connecting the same to said supports, preformed panels of thin sheet composition material detachably secured in the baggage rack cove and preformed panels of thin sheets of composition material detachably secured in the ceiling coves of said car.
4. In a railway car having an inner wall comprising header, wainscoting and pilaster panels, said pilaster panels being preformed to form columns, and clips for detachably connecting said panels in position within said car, said panels being preformed and provided with attaching clips whereby the same conforms to the shape of the interior of said car and may be readily attached and detached.
5. A passenger car comprising roof, floor, side and end walls, side posts between said roof and

floor along the sides of said car, windows between said posts along each side of said car frames for said windows between said posts along each side of said car, frames for said windows, plates rigidly secured to said side posts and provided with openings, wainscoting panels provided with resilient clips for detachably engaging said openings for detachably securing said panels to said strips beneath said windows, said panels having their edges curved outwardly and engaging alongside the edges of said frame, header panels having resilient clips extending outwardly therefrom for detachably engaging openings in said plates above said windows for holding said header panels above said windows and pilaster plates having spring clips thereon for engaging said openings for holding said pilaster plates in position between said windows, the edges of said pilaster plates offset inwardly and being curved outwardly and engaging the aligned edges of said panels and frame.

6. In a railway car having a ceiling and side walls, a plurality of windows in the side walls, a flanged side post at each side of each window, openings through the flanges of said posts, curved upturned bars connecting the posts between the windows, a preformed trim window panel having out-turned edges above each window, a preformed wainscoting finish panel having out-turned edges below each, a pilaster finish panel extending from the ceiling to the floor between the windows and having out-turned edges engaging the out-turned edges of said window and wainscoting finish panels, and clips carried by said panels for detachably engaging the openings and apertures within said flanges and strips.

7. In a railway car having a frame including flanged side posts, an outer wall secured to said side posts, windows between said posts, preformed panels of composition material below said windows between said posts, a preformed pilaster panel of composition material extending over the posts between said windows and having its side edges turned outwardly and engaging the panels above and below the adjacent windows and clips carried by said pilaster panel for detachably engaging one of the flanges of said posts for holding said pilaster panel in operative position simulating a column between said windows.

8. A method of finishing the interior side walls of railway cars comprising constructing the inner walls of said car in separate window, pilaster and wainscoting panels, preforming said panels, embossing and finishing each panel separately, detachably connecting the panels to the interior of the car by resilient clips and then detachably connecting the lamp supports and baggage racks over the window and pilaster panels.

9. A method of finishing the interior of railway cars which comprises constructing the finish walls of separate panels of composition material, preforming said panels, embossing and covering said walls on one side with a fabric including clips, means for detachably connecting said panels to the interior of the car and baggage racks detachably connected to the side walls of said car above said panels.
